UNITED STATES PATENT OFFICE

ROBERT MORRIS SUTPHEN, OF NEWARK, NEW JERSEY

DESIGN FOR A SURFACE TILE FOR A WALL CAP COURSE

Application filed November 29, 1929. Serial No. 33,579. Term of patent 14 years.

To all whom it may concern:

Be it known that I, ROBERT MORRIS SUTPHEN, a citizen of United States, and resident of city of Newark, in the county of Essex and State of New Jersey, have invented a new, original, and ornamental Design for a Surface Tile for a Wall Cap Course, of which the following is a specification, reference being had to the accompanying drawing, forming part thereof.

Figure 1 is a front elevation of a surface tile for a wall cap course showing my new design, and

Figure 2 is a top plan view thereof.

I claim:

The ornamental design for a surface tile for a wall cap course, as shown.

ROBERT MORRIS SUTPHEN.
